DAKOTA.

PENETRATION-DETERMINING DEVICE FOR ASPHALT.

1,366,572.

Specification of Letters Patent. Patented Jan. 25, 1921.

Application filed March 13, 1919. Serial No. 282,388.

To all whom it may concern:

Be it known that I, LEROY M. LAW, a citizen of the United States, residing at city of Baltimore, in the State of Maryland, have 5 invented new and useful Improvements in Penetration-Determining Devices for Asphalt, of which the following is a specification.

This invention relates to rotary calculators of that type in which concentrically mounted disks or equivalent elements are provided, which disks carry markings or legends adapted to be positioned adjacent or in predetermined relation to one another, 15 certain of the disks being provided with suitable apertures through which certain characters indicative of a predetermined result may be read.

In the embodiment of the invention disclosed herein, the device is adapted to the specific purpose of determining the consistency, or, as it is known in the art "penetration" of bituminous or similar compositions, in order to insure the selection of that 25 composition best adapted for constructing certain classes of roadway under certain known conditions of traffic and climate.

The present embodiment of the invention comprises a base portion laid off or arranged 30 in sectors and having mounted thereon two disks of successively larger diameters having sectors defined on their surfaces, but it is to be understood that a greater number of disks may be so mounted, and, furthermore, that 35 they may be mounted upon both faces of the base portion if desired. It will be obvious also that the shape of the disks may be changed and reading openings and legends variously disposed without departing from 40 my invention.

Referring to the drawings, like numbers indicating like parts in the several views:

Figure 1 shows the three disks in separated condition;

Fig. 2 is a plan view of the disks assembled and set for reading;

Fig. 3 is a section taken on line 3—3 of Fig. 2;

Fig. 4 is a sectional view showing disks 50 on both sides of a base.

The base portion 10 comprises a block or disk of wood, cardboard, fiber or other suitable material, said base 10 having on its face, suitable characters or legends 11 arranged

in the peripheral margin thereof, which 55 legends indicate standard roadway constructions. Radially disposed from the center of the base portion 10 are series of numerals designated as 12 in the drawing. These legends and characters on the base 10 are, as 60 shown in Fig. 1, arranged in sectors each legend having at the inner end of its sector an appropriate group of numerals circularly arranged and radially aligned.

Concentrically and rotatably mounted on 65 the base portion 10 is a disk 13 of smaller diameter than the base portion 10, bearing in certain spaced relation on its peripheral margin certain legends 14 indicating climatic or temperature conditions, and having 70 apertures 15, through which the numerals upon the face of the base portion 10 may be read when said disk 13 is brought to proper position. It will be seen that the number of legends or sectors on the disk 13 is one less 75 than those on the base. With this arrangement no confusion in reading the legends on the base and disk will occur, for when one of the disk legends is in registry with a base legend, the other legends on the disk are 80 thrown out of registry, and do not give a registered reading.

Concentrically and rotatably mounted with respect to said disk 13, is a third disk 16 of still smaller diameter bearing on its 85 upper face and in certain spaced relation on the peripheral margin thereof certain legends and markings 17 which indicate various usual traffic conditions. The said disk 16 has therethrough suitably disposed apertures 18 which are adapted, upon rotation of the disks, to register with the apertures 15 in the lower disk 13 and thereby permit a reading of the numerals 12 on the face of the disk 10. This second disk has the same number 90 of legends as the first and when the two disks are brought into registry with the legend on the base to give a reading, the other legends on the second disk will be out of 95 register with the base legends.

The disks may be fastened for rotation by any suitable means, as 19, which may be a thumb tack, nail, screw, or nut and bolt, as herein shown.

I preferably separate the legends appearing on the two rotatable disks 13 and 16 by areas 20 of contrasting appearance or color, said areas 20 being of the same circumfer-

ential length so that when any two are brought into registry with each other, as in Fig. 2 of the drawings, the temperature and traffic legends are in proper registry with each other, and when the rotatable disks 13 and 16 with their registered legends are brought to the position shown in Fig. 2 with the radial boundary line of the registered contrasting areas in alinement with the dividing line on the base or lower disk 10, the temperature and traffic conditions are in proper position with respect to the roadway legend appearing on the lower disk or base 10. By providing these contrasting areas, positioning of the disks for proper reading with respect to any of the roadway constructions specified is comparatively easy, and the said areas 20 are so proportioned as that when any two are registered and the disks are brought to a reading position with respect to any specified roadway construction, the other contrasting areas and legends are offset and do not give a reading relation of legends or numerals. 25 In other words, the contrasting areas 20 serve as a guide for positioning the disks and eliminate any chance of mis-reading.

The use of the device is as follows:

When it is desired to ascertain the penetration or consistency of the mixture to be used in making a roadway of certain material or composition; the climatic and traffic conditions being known, the legend for the class of roadway on the base portion, the temperature or climatic legend on the next upper disk, and the traffic legend on the third disk, are positioned in registering relation radially, as shown in Fig. 2 of the drawings, by rotation of the disks. The result, which is the penetration or consistency of the composition best suited to that particular class of roadway under the climatic and traffic conditions indicated, may then be read immediately below the registered legends through the reading apertures described.

In the example shown in Fig. 2 of the drawings, the device is set to ascertain the penetration desirable in an "asphalt macadam (hot mix)" roadway; under the climatic conditions where "moderate temperatures" prevail, and where there is "moderate traffic". For these conditions, as indicated by the number appearing through the reading apertures, a penetration of seventy-five is the most satisfactory.

In Fig. 4 the device is shown as having two sets of disks, one on either side of the base or central disk 21, a single fastening 60 means 22 serving to fasten both sets of disks in place. It will be obvious that this arrangement increases the capacity of the device and doubles the computations which can be made.

65 This device is of practical value to high-

way engineers and all road makers, as it shows at a glance and in a simple and easily understandable form the penetration for all standard composition roadways under different temperatures and traffic conditions. It 70 should also be noted that this device is so constructed that for the sake of accuracy and to prevent confusion and mistakes on the part of the person using the calculator, that when the legends are positioned adjacent one 75 another for computation, all other elements necessary to a computation are out of position. This is illustrated in Fig. 2 of the drawings and holds true for all positions to which the calculator may be set.

Such changes in construction and disposition of parts as are within range of mechanical skill may, of course, be made without departing from the spirit of my invention.

I claim:

1. In a device of the class described, a base having its face arranged to present a plurality of sectors; a legend at the outer edge of said base opposite each sector and a plural series of characters arranged at the inner portion of each sector; a disk of smaller area than said base rotatably mounted thereon and having adjacent its edge a less number of legends than the number of legends on said base, any one of which disk 95 legends is adapted to register with any of the legends on said base, said disk being provided in its central portion with radially off-set slots, one for each series of characters; and a second disk of smaller area than said first named disk 100 mounted on said base and having legends equal in number to the legends on said first-named disk adjacent its edge adapted to register with any of the legends on said first-named disk 105 and any one of the legends on said base, said second disk having slots therein, any one of which is adapted to register with any one of the radially off set slots to permit selective reading of the characters in any one of the 110 sector areas on the said base when said disks are brought to predetermined positions.

2. In a device of the class described, a base having its face arranged to present a plurality of sectors; a legend at the outer 115 edge of said base opposite each sector and a plural series of characters arranged at the inner portion of each sector; a disk of smaller area than said base rotatably mounted thereon and having adjacent its edge a less number of legends than the number of legends on said base which are separated from one another by contrasting areas and any one of which disk legends is adapted to register with any of the legends on said base, said disk being provided in its central portion with radially off-set slots, one for 120 each series of characters; and a second disk of smaller area than said first-named disk 125 rotatably mounted on said base and having

- legends equal in number to the legends on said first-named disk adjacent its edge adapted to register with any of the legends on said first-named disk and any one of the legends on said base, said second disk having slots therein any one of which is adapted to register with any one of the radially off-set slots to permit selective reading of the characters in any one of the sector areas on the said base when said disks are brought to predetermined positions.
3. In a device of the class described, a circular base having a plurality of legends circumferentially arranged at its outer edge and a plural series of characters circularly disposed at its central portion; a disk of smaller diameter than said base rotatably mounted thereon and having a less number of legends than the number on said base circumferentially arranged at its outer edge any one of which is adapted to register with any one of the legends on said base, said disk being provided with slots adapted to register with the centrally disposed characters on said base; and a second disk of smaller diameter than said first-named disk having legends arranged at its outer edge equal in number to the legends on said first-named disk and adapted to register there-
- with and with the legends on said base, said second disk having slots any one of which is adapted to register with the slots in said first-named disk to permit selective readings of the characters on said base.
4. In a device of the class described, a base having a plurality of circumferentially disposed legends at its edge and a plurality of characters at its central portion; a disk of smaller area than said base having a plurality of legends less in number than the legends on said base at its outer edge, any one of which legends can be brought into register with any legend on said base with the other legends on said disk out of registry with the other legends on said base, said disk having a reading slot therethrough for said centrally disposed characters; and a second disk of smaller area than said first-named disk provided with legends at its edge, any one of which may be brought into register with any one of the legends on said first-named disk and said base and a slot in said second disk adapted to register with the slot in said first-named disk.
- In testimony whereof I have hereunto set my hand.

LEROY M. LAW
